METHOD AND MEANS FOR CONTROLLING
THE FLOW OF LIQUID

Carlyle M. Ashley, Maplewood, N. J., assignor, by
mesne assignments, to Carrier Engineering
Corporation, Newark, N. J., a corporation of
New York

Application December 2, 1933, Serial No. 700,670

13 Claims. (Cl. 62—152)

This invention relates to a refrigeration system, and more particularly, to the disposal of liquid condensate from the condenser of such a system.

5 It is an object of this invention to remove a volume of condensate from a condenser maintained at sub-atmospheric pressure, to supply a portion of the condensate to an evaporator maintained at an even lower pressure, and to 10 discharge the remaining condensate at atmospheric pressure over the surfaces of the condenser.

Another object of the invention is to control the flow of liquid to an evaporator from a condenser located below the evaporator.

15 A further object of the invention is to utilize a pressure difference for lifting a liquid from one level to another, and to augment this lifting effect by introducing vapor into the liquid to be lifted.

20 Still another object of the invention is to supply a liquid to an evaporator from a source located below the evaporator, and to prevent the siphoning of liquid from the evaporator when 25 the pressure in the evaporator is equal to the pressure at the source.

Another object of the invention is to withdraw 30 a portion of condensate from the inside of a condenser, to discharge this condensate over the outer surfaces of the condenser, and to prevent a flow of water into the condenser whenever the condenser is inoperative.

35 A feature of the invention resides in the provision of an inverted liquid trap between an evaporator and a condenser located below the evaporator.

Still another feature of the invention resides in the provision of means for admitting vapor to the condensate in the leg of the inverted trap 40 which is subjected to condenser pressure.

Still another feature of the invention resides in the provision of a siphon breaker in the leg of the inverted trap which passes into the evaporator.

45 A further feature resides in provision of a circuit for supplying liquid over the surfaces of a condenser, an aspirator in said circuit for withdrawing liquid from the inside of the condenser, and an inverted trap in the liquid circuit for preventing the flow of liquid from said circuit into the condenser.

Other objects and features of the invention will in part be obvious and will in part appear hereinafter.

55 Fig. 1 is an elevational view, partly in section,

of a refrigerating system, of the steam ejector type, suspended from the floor of a conventional railroad car;

Fig. 2 is a sectional elevational view of a portion of the apparatus of Fig. 1;

Fig. 3 is a fragmentary view of a float check valve which may be used in connection with the apparatus of Fig. 1.

With reference to the drawing, similar designations referring to similar parts, Fig. 1 shows a refrigeration apparatus of the steam ejector type to which this invention is particularly applicable, though to which it is in no sense limited. The apparatus comprises an evaporator 5 in which is a body of water 6 in open communication with head 7 and entrance diffuser 8 of a steam ejector generally designated by numeral 9. In operation, steam admitted through pipe 10, is expanded, by means of a suitable nozzle positioned within head 7, to a desired low pressure. The high velocity jet of steam issuing from the nozzle entrains water vapor from evaporator 5, thereby lowering the pressure therein. Consequently, water 6 boils, thus absorbing heat at a desired low temperature. The remaining water is withdrawn through pipe 11, utilized for any desired purpose, for example, to cool air, and returned to the evaporator through spray pipes 12. The mixture of steam and entrained water vapor, after being compressed in diffusers 8 and 13, is discharged into inlet header 14, and distributed throughout the tubes 15 of condenser 16. The resulting condensate is collected in the discharge header 17 from which it flows by gravity through pipe 18 into a collecting well 19.

An inverted trap 20 joins well 19 and evaporator 5. Due to the difference in the pressures existing in evaporator 5 and condenser 16, condensate from well 19 flows upwardly through the high pressure leg 21 of trap 20 and discharges 40 into evaporator 5 through low pressure leg 22. It is apparent that as the liquid rises in leg 21, the pressure to which it is subjected falls. A hole 23 in the high pressure leg 21, located within well 19, but above the normal liquid level, allows vapor from the well to pass into the liquid condensate in leg 21. This, in combination with the boiling which must occur due to the falling pressure referred to above, results in an ebullition of vapor throughout the liquid in leg 21, which, in turn, causes a reduction in the amount of liquid contained in any given volume of the leg 21. Consequently, a relatively small pressure difference will be sufficient to force the con- 50 55

densate over the "hump" in inverted trap 20, and into evaporator 5.

The pressure existing in condenser 16 varies with each change in outside weather conditions, 5 whereas the pressure in evaporator 5 remains substantially constant. Therefore, leg 21 of trap 20 must be so designed that a minimum pressure difference, plus the vapor lift effect just described, will be sufficient to force the requisite quantity 10 of liquid from well 19 into evaporator 5. However, when the pressure difference is above this minimum, the flow of liquid from the well, if uncontrolled, would be in excess of that actually required, and would, therefore, tend to increase the 15 liquid level in evaporator 5 above the desired point. To control the liquid flow, applicant provides a hollow ball 24 floated by liquid in well 25 of evaporator 5. As the liquid level in the evaporator rises responding to liquid flow from trap 20, 20 the ball is floated against the open end of low pressure leg 22. Conversely, as the liquid level falls, ball 24 is floated away from the end of leg 22, and a flow of liquid into the evaporator is again established. Preferably, ball 24 is made of 25 rubber, because of its resiliency. Hence, when the ball is floated against the end of leg 22, the rubber surfaces "give", thus compensating for any irregularities in the seat.

Whenever the ejector is inoperative, i. e., no 30 steam is supplied to the nozzle through pipe 10, the pressures in evaporator 5 and condenser 16 are equalized through diffusers 8 and 13. Further, the water in the cooling circuit, including pipe 11, spray pipes 12, and an air cooling coil 35 (not shown) flows back into evaporator 5, thus materially raising the liquid level therein. If, then, when the system is inoperative, float ball 24 should fail to seat properly, it is apparent that trap 20 would constitute a perfect syphon, and 40 consequently, liquid would flow from evaporator 5 into condenser 16. To prevent this possibility, applicant provides a hole 26 in low pressure leg 22 at a point above the maximum liquid level in evaporator 5. Thus, any possible syphon is 45 effectively broken.

As can be seen in Fig. 1, head 7 of ejector 9, for 50 purposes of space economy, is joined to an end of evaporator 5. If the level of water in the evaporator should rise, as under conditions described above, it is apparent that the water would flow 55 through the ejector and thence into condenser 16. To prevent this, applicant provides a U-shaped trough 41, extending from head 7 throughout the length of the evaporator 5. In this manner, open communication between the evaporator and ejector is maintained, but passage of water therethrough effectively prevented.

For the purpose of liquefying the compressed vapors in condenser 16, applicant utilizes the principles of evaporative cooling. To this end, water 60 from sump 27, through pipe 28, pump 29, inverted trap 30, aspirator 31, pipe 32, and header 33 is sprayed over the surfaces of tubes 15. Air flowing in the direction indicated by the arrows, contacts the wet tube surfaces, absorbs a part of the water vapor, and consequently, tends to cool the condenser to a temperature corresponding to the wet bulb temperature of the incoming air. The moisture laden, heated air is discharged upwardly 65 through louvres 34.

Obviously, some of the water from sump 27 is 70 constantly being lost through this evaporative process. To make up for this loss, at least partially, applicant withdraws from condenser 16 that 75 quantity of water corresponding to the steam

supplied through pipe 10 and discharges it over the condenser surfaces. To this end, condensate from well 19, through pipe 35, and float check valve 36, is supplied to aspirator 31, and therein mixed with water from sump 27. The remaining 5 water deficiency is supplied to sump 27 from an auxiliary make-up water tank or other means (not shown).

As is well understood, the condenser and evaporator are both operated at pressures well 10 below atmospheric, for example, at pressure ranging from 27-29.5 inches of vacuum. Therefore, when the system is inoperative, including pump 29, water from sump 27 would tend to flow 15 through aspirator 31, pipe 35, and well 19 into the condenser. To prevent this, check valve 36 is provided in pipe 35. As can be seen from Fig. 3, water rising in pipe 35 will force ball 37 against seat 38, thus stopping any upward flow of liquid.

However, even the best check valves tend to 20 leak. As an additional safety feature, applicant provides inverted trap 30, and a passageway 39, connecting the top of trap 30 with pipe 32. A swing check valve 40, of well known design, opens in the direction indicated by the arrow 25 42. If check valve 36 leaks, water is drawn into the condenser both from pipe 32 and from one leg of trap 30. A movement of liquid in trap 30 causes check valve 40 to open, thus providing a 30 passageway to atmospheric pressure. Consequently, when all the water in pipe 32, one leg of trap 30, and passageway 39 is drawn into condenser 16, the vacuum is broken, the condenser fills with air, and any water contained therein 35 drains from the condenser by gravity. This feature is of particular importance in preventing freezing of the condenser under certain conditions.

Aspirator 31 serves, in a well understood manner, the additional purpose of purging the system 40 of air, and other non-condensable gases prior to, and during operation.

Since certain changes in carrying out the above 45 process and in the constructions set forth, which embody the invention may be made without departing from its scope, it is intended that all matter contained in the above description or shown in the accompanying drawing shall be interpreted as illustrative and not in a limiting sense.

I claim:

1. In a refrigeration apparatus, an evaporator, a condenser, a steam ejector (connecting said evaporator and condenser, a well for collecting liquid from said condenser, an inverted trap connecting said well and said evaporator for supplying a portion of the liquid from said well to said evaporator, means for controlling the flow of liquid through said trap, and means for discharging the remaining portion of said liquid over the surfaces of said condenser.

2. In a refrigeration apparatus, an evaporator, a source of liquid located below said evaporator, an inverted trap connecting said evaporator and said source, and a siphon breaker in said trap for preventing flow of liquid from said evaporator to said source, said siphon breaker comprising an opening in the trap between the extremities thereof.

3. In a refrigeration apparatus, an evaporator, a source for supplying liquid to said evaporator, an inverted trap connecting said evaporator and said source, means responsive to changes in the liquid level in said evaporator for controlling the flow of liquid from said source to said evaporator,

- and means for preventing a flow of liquid from said evaporator to said source.
4. In a refrigeration apparatus, an evaporator, a condenser, and an ejector connecting said evaporator and condenser, means for supplying a portion of liquid from said condenser to said evaporator, means for supplying another portion of said liquid to the outer surfaces of said condenser, a siphon breaker for preventing a flow of liquid 5 from said evaporator to said condenser, and a vacuum breaker for preventing a flow of liquid into said condenser from an outside source.
5. In a refrigeration apparatus, an evaporator, a condenser the lower portion of which is below 15 said evaporator, an ejector connecting said evaporator and the upper portion of said condenser, an inverted trap for supplying a portion of liquid from the lower part of said condenser to said evaporator, means for preventing a flow of liquid 20 from said evaporator to said condenser, means for supplying the remaining portion of said liquid to the outer surfaces of said condenser, and means for preventing a flow of liquid into said condenser from an outside source.
- 25 6. In a refrigeration apparatus, a condenser, a liquid sump located below said condenser, a liquid circuit for conveying water from said sump to the outer surfaces of said condenser, an aspirator in said circuit for withdrawing air and a portion 30 of liquid from said condenser, and means for preventing a flow of liquid from said circuit into said condenser.
7. In a refrigeration apparatus, a condenser, a liquid sump located below said condenser, a liquid 35 circuit for conveying liquid from said sump to the outer surfaces of said condenser, an aspirator for introducing into said circuit liquid from the condenser, and a vacuum breaker in said circuit between said sump and said aspirator.
- 40 8. In a refrigeration apparatus, a condenser, a liquid sump located below said condenser, a header for spraying liquid over the surfaces of said condenser, a liquid circuit connecting said sump and said header, means for introducing into 45 said circuit liquid from the condenser, an inverted trap in said circuit between said means and said sump and means for admitting air into the top of said trap for preventing a flow of liquid from said circuit to said condenser.
9. In a refrigeration system, an evaporator, a condenser, a well for collecting condensate from the condenser, an inverted trap connecting said well and the evaporator, means for controlling the flow of liquid through the trap to the evaporator, and means for drawing liquid from the well 5 for use in cooling the condenser.
10. In a refrigeration system of the character described, an evaporator, a condenser, a well for collecting condensate from the condenser, an inverted trap connecting the well to the evaporator, a float ball for controlling the flow of liquid 10 through the trap, the ball being arranged to stop the flow of liquid through the trap by pressing within the pipe opening constituting the 15 evaporator end of the trap when the liquid in the evaporator rises above a prescribed level, the ball dropping from its abutting position when the liquid in the evaporator falls below the prescribed 20 level.
11. In a refrigeration system, an evaporator, a condenser, a receptacle for collecting condensate from the condenser, a trap connecting the receptacle and the evaporator, and means comprising a conduit having an open end submerged in liquid 25 within the receptacle and an opening in the conduit above the level of liquid in the receptacle, the conduit constituting one leg of the trap, said opening permitting the introduction of vapor within said leg whereby a mixture of vapor and 30 liquid will be formed in the leg.
12. In a system of the character described, an evaporator, a condenser, a collecting chamber for receiving condensate from the condenser, means for supplying liquid from said chamber to the 35 evaporator, the pressure in the evaporator being less than atmospheric and means for supplying liquid from the chamber to the outer surface of the condenser under atmospheric pressure.
13. In a system of the character described, a condenser, a chamber for receiving condensate from the condenser, means for supplying liquid from the chamber to a receptacle under a vacuum, a pump circuit, means in the pump circuit for drawing another portion of the liquid from the 40 chamber, and means for passing said other portion of the liquid in heat exchange relation with the condenser.

CARLYLE M. ASHLEY.
